J. L. SMITH

SAFETY BILL HOLDER

Filed Dec. 8, 1921

INVENTOR:

JOHN L. SMITH,
BY: Otto H. Kueger,
his Atty.

UNITED STATES PATENT OFFICE.

JOHN L. SMITH, OF LOS ANGELES, CALIFORNIA.

SAFETY BILL HOLDER.

Application filed December 8, 1921. Serial No. 521,019.

To all whom it may concern:

Be it known that I, JOHN L. SMITH, a citizen of the United States, residing at Los Angeles, in the county of Los Angeles and 5 State of California, have invented a new and useful Safety Bill Holder, of which the following is a specification.

This invention relates to devices, such as purses, wallets, and pocket-books, for holding 10 paper currency, notes, bills, and other similar valuable matter.

One of the objects of this invention is to provide a device of this type with catching means to protect against loss or theft.

15 Another object is to provide a device which will hold bills securely and yet allow a proper removing without excessive or undue trouble.

Another object is to provide a device in 20 which bills are disposed flat between rollers.

Another object is to assure convenience and at the same time security in connection with bills carried in pockets.

Other objects will appear from the following 25 description and appended claims as well as from the accompanying drawing, in which—

Fig. 1 is a perspective view of a bill-holder embodying this invention.

30 Fig. 2 is a midsectional view of the fastening and catching end of the device in Fig. 1.

Fig. 3 is a fragmentary top plan view of a frame for holding the rollers.

35 Fig. 4 is a side elevation of the rollers and bottom spring illustrating the co-action of the bottom spring and some of the rollers.

Fig. 5 is a cross section through the bottom spring in connection with the arrangement of three rollers, two of the rollers to be 40 operatively connected to one of the cover plates, the other roller to be operatively connected to the opposite cover plate, illustrating the relative positions of bills in the device.

Fig. 6 is a cross section through a device in a slightly modified form, having one roller in operative connection with each of the cover plates.

50 Fig. 7 is a cross section through a device of a still more slightly modified form, having a flexible flap on one of the cover plates to be wound around or folded and closed over the inclosed bills.

55 As illustrated in Fig. 1, the device can be opened so that bills can easily be placed in

a flat condition between the two sets of rollers or between the rollers and the flat springs. In the form illustrated in Fig. 1, the device is provided with two outside or cover plates 8 and 9, hingedly connected at 10. A spring 11 of coil form is inserted between the cover plates at the hinge end, to cause the cover plate 9 to move to the opened position in which it is illustrated, in relation to the other 60 cover plate 8, as soon as it is released from the locking catch 12. A roller 13 is turnably disposed between the lugs 14 on the cover plate 9. Two other rollers are turnably mounted within a frame-like structure, 70 the rollers being indicated at 15. The frame consists of the end member 16, the connecting members 17 and 18, and the end member 19. The end member 16 of the frame is preferably hingedly connected with the 75 cover plate 8, as indicated at 20, so that the frame can also be moved in relation to the cover plate 8 to a similar extent as the cover plate 9, the locking catch 21 holding the frame in closed or locked position in relation 80 to the cover plate 8. The frame is illustrated in detail in top plan view in Fig. 3. A flat spring 22 is preferably inserted between the cover plate 8 and the rollers 15, spring and rollers being illustrated in side 85 elevation in Fig. 4. The flat spring 22 serves to form a suitable friction means for the rollers, so that bills inserted between the roller 13 and the rollers 15 are suitably retained in the device. Bills can also be inserted between the spring 22 and the rollers 15, since the rollers 15 with the frame are 90 hingedly connected to the cover plate 8. The spring 22 holds in this case the bills against the rollers 15.

95 As illustrated in Fig. 5, bills, indicated in dotted lines at 23, will easily slide through the space between the rollers 15 on one side and the roller 13 on the other side; and, if the rollers are arranged closely, the bills 100 can be pulled out as long as the rollers turn. The bills, indicated in dotted lines at 24, placed between the flat spring 22 and the rollers 15, are only detained by the tension of the spring 22 and slide easily through the 105 device.

In the slightly modified form in Fig. 6, the roller 25 is turnably mounted on the inner face of the cover plate 9 and the roller 26 is turnably mounted on the inner face of 110 the cover plate 8. An inserted bill slides normally along the dotted line 27 through

the device passing between the rollers 25 and 26.

The slightly modified form in Fig. 7 illustrates a general cross section through the 5 rollers 13 and 15 and through the cover plates 8 and 9, a flap 28 being added to one of the cover plates to be folded together with the inserted bills so as to cover the bills, keeping the whole in a closed condition.

10 A catching or safety means is provided in the one end of the device, illustrated in midsectional view in Fig. 2. This safety device can, of course, be used in connection with many other articles, carried in pockets 15 or on the body of people, especially all such articles that are attached to chains or cords or similar means. The main object of this device is to operate suitable catching means by a pulling of the chain, cord, or other 20 similar means, so that the article to be protected by the device cannot be pulled or removed from the body of the person using this device without attracting the attention of the person. A slight pulling on the attaching end 29 against the tension of the 25 spring 30 brings the pointed or engaging ends 31 out of their concealed or inoperative positions, to catch in the clothing of the person or otherwise attract attention by resisting such a pulling from the outside. This device can be modified to quite an extent 30 to suit the conditions or constructions of different articles as long as the resisting qualities are present against an outside pulling. This catching or safety device, when 35 applied to an article carried in a pocket, is not removed from the pocket by a pulling of the chain or similar means by which it is operated but by reaching into the pocket

and grasping the whole article to which the 40 safety means is applied, to avoid a protruding or operating of the catching means.

Having thus described my invention, I claim:

1. In a device of the class described, cover 45 plates having hinge connection at one end and having a lock at the opposite end, and rollers on the inner faces of the cover plates.

2. In a device of the class described, cover 50 plates hingedly connected at one end, rollers on the inner faces of the cover plates, a flat spring below one of the rollers adjacent one of the cover plates, and locking means for holding the rollers in a parallel position.

3. In a device of the class described, cover 55 plates connected at one end for a swinging movement to one another, a roller frame having means swingably connecting with one of the cover plates, rollers mounted in the roller frame and on the inner face of 60 the opposite cover plate in parallel relation to one another when in closed position, and locking means for holding the rollers in parallel position.

4. In a device of the class described, cover 65 plates having hinge connection at one end and having a lock at the opposite end, rollers on the inner faces of the cover plates, and a safety catch on one of the ends of the 70 device.

In testimony that I claim the foregoing as my invention I have signed my name in the presence of two subscribing witnesses.

JOHN L. SMITH.

Witnesses:

O. H. KRUEGER,
JESSIE A. MANOCK.
